COMBINED BED AND BOOKCASE UNIT

Norman H. Fowler, Morristown, Tenn., assignor to Forest Products Corporation, Morristown, Tenn., a corporation of Tennessee

Continuation of design applications Ser. No. 86,248 and Ser. No. 86,249, July 22, 1965. This application June 20, 1966, Ser. No. 2,731

Term of patent 14 years

(Cl. D5—4)

FIG. 2

FIG. 1 is a perspective view of a combined bed and bookcase unit, showing my new design, in which the support for the bookcase is a kneehole desk.

FIG. 2 is a perspective view of a combined bed and bookcase unit, showing my new design, wherein the support for the bookcase is a chest of drawers.

In each instance, the rear of the bookcase and of the support is substantially plain and unornamented; and the side not shown is identical with the side shown.

This application is a continuation of my earlier filed applications Serial Nos. D-86,248 and D-86,249 both filed on July 22, 1965.

I claim:

The ornamental design for a combined bed and bookcase unit, as shown and described.
